UNITED STATES PATENT OFFICE.

THOMAS J. BRINER, OF READING, PENNSYLVANIA, ASSIGNOR OF ONE-HALF
TO THOMAS D. BAUSHER, OF READING, PENNSYLVANIA.

TREE-HOLDER.

SPECIFICATION forming part of Letters Patent No. 727,074, dated May 5, 1903.

Application filed November 11, 1902. Serial No. 130,842. (No model.)

To all whom it may concern:

Be it known that I, THOMAS J. BRINER, a citizen of the United States, residing at Reading, in the county of Berks and State of Pennsylvania, have invented certain new and useful Improvements in Tree-Holders; and I do hereby declare the following to be a full, clear, and exact description of the invention, such as will enable others skilled in the art to which it appertains to make and use the same.

This invention relates to improvements in tree-holders, and is particularly adapted for holding the so-called "Christmas tree" in position on either the floor or other suitable place; and the object of the same is to produce a simple construction which will be cheap to manufacture and effective in operation.

To this end my invention consists in the details of construction hereinafter more fully set forth and claimed in the following specification and as illustrated in the accompanying drawings, in which like reference characters designate similar parts in the different views.

Figure 1 is an elevation, and Fig. 2 a plan view, of my device.

My invention consists, preferably, of two independent sections or members A, provided with concaved inner faces approximately V-shaped in form and of the same diameter throughout the entire length, each section or member being provided with a flaring base a. In this base portion at approximately its central point is provided an outwardly-opening slot b, suitable for engaging a screw. The vertical apex c of each V-shaped face of the members is slightly flattened, and passing through the flattened portion are a plurality of vertically-alined transverse apertures or openings b'.

In operation one section or member is secured in any desired position to the floor

or other support by means of a screw engaging the slot b, and the trunk of the tree is placed in position against the inner concaved 45 face of said member. The other section or member is then placed in position and pressed against the tree-trunk opposite the first section or member and is also secured to the floor by means of a screw engaging the outwardly-opening slot in the base thereof. One or more screws or nails may be inserted through the transverse openings or apertures b' in each section or member A into the tree-trunk for holding the same securely in position to prevent displacement of the parts.

This device may be made of any size and material to accommodate larger or smaller trees, as may be desired. The inner face of each member or section A being of approximately V shape allows the tree-trunk to be forcibly wedged into position, causing the same to be gripped firmly tending to more effectively hold the same in position.

Having thus described my invention, what I claim as new, and desire to secure by Letters Patent, is—

A device of the class described comprising two independent members, each member being provided with a concaved inner face approximately V shape in form and of a uniform diameter through its entire length, the apex of the face of each member being slightly flattened and provided with a plurality of vertically-alined transverse apertures, and a projecting flange at the base of each member, said flange being provided with an outwardly-opening slot.

In testimony whereof I affix my signature in presence of two witnesses.

THOMAS J. BRINER.
